UNITED STATES PATENT OFFICE.

HENRY SELBY HELE-SHAW, OF LONDON, ENGLAND.

RADIAL-CYLINDER HYDRAULIC CLUTCH.

Application filed January 17, 1920. Serial No. 352,167.

(GRANTED UNDER THE PROVISIONS OF THE ACT OF MARCH 3, 1921, 41 STAT. L., 1313.)

To all whom it may concern:

Be it known that I, HENRY SELBY HELE-SHAW, subject of the King of Great Britain, and a resident of London, England, have invented certain new and useful Improvements in Radial-Cylinder Hydraulic Clutches, (for which I have filed application for patent in Great Britain No. 1010, dated January 14, 1919, and obtained British Patent No. 142,901), of which the following is a specification.

My invention relates to an improved form of radial cylinder hydraulic clutch.

In the specification of my prior application Serial No. 311,311, I explained that hydraulic clutches embodying the principles upon which the invention dealt with in that specification depended could be either of radial or parallel type, and details were given of a parallel type of clutch, in which single or double swash plates were employed.

The present invention comprises a hydraulic power transmitting shaft clutch consisting of a rotary member adapted to be rotated by the power shaft and provided with, or constructed with, a number of radially arranged cylinders. These cylinders are fitted with pistons adapted to be operatively connected with a corresponding number of cranks or eccentrics formed on the driven shaft of the clutch. The fluid is adapted to be admitted to the pistons by means of inlets arranged in the ends of the cylinders and placed in communication

with one another by means of a closed fluid passage provided with a number of valves corresponding to the number of the said cylinders and arranged to cut off or control such communication when operated by means provided for the purpose. The cylinders may be arranged in groups those in each group being placed in communication with one another by means of an independent closed fluid passage.

The pistons of the cylinders are preferably connected to the cranks or eccentrics by means whereby the objection arising from the oblique action of connecting rods is avoided. This is effected by arranging the cylinders diametrically in co-axial pairs and with open ends towards the axis of the clutch. The two pistons of each pair of

diametrically arranged cylinders are connected together by means of a yoke or rectangular frame arranged to extend around an associated crank or eccentric formed on the driven shaft. These frames are placed in operative contact with the said crank or eccentric by means of oppositely disposed bearing members curved on their inner sides to engage the said cranks or eccentrics and provided with flat outer surfaces adapted to bear against and slide on the inner faces of the said yoke frame at right angles to the common axis of the said pair of cylinders.

The control valves may be arranged to be operated mechanically or hydraulically in some cases means being provided whereby both systems can be used on the same clutch.

Means are provided for maintaining the closed fluid passage completely full during the operation of the clutch, and the said passage is preferably provided with a safety valve to avoid excessive fluid pressure accumulating therein.

In the preferred form of the clutch the cylinders are arranged on the driving element of the clutch. They may, however, be arranged on its driven element.

In the forms of the invention illustrated in the accompanying drawings—

Fig. 1 is a longitudinal sectional view of a clutch having four medial cylinders arranged in two pairs side by side.

Fig. 2 is a transverse sectional view of the same clutch on the line 2—2 of Fig. 1.

Fig. 3 is a sectional view showing one of the controlling valves on the line 3—3 of Fig. 2.

Fig. 4 is a longitudinal sectional view of a clutch having eight cylinders arranged in two sets each having four cylinders with their axes at 90° to one another.

Fig. 5 is a view showing the means of connecting the oppositely disposed pistons of the construction shown in Fig. 4.

Fig. 6 is a sectional view showing controlling valves adapted to be operated hydraulically and mechanically.

Figs. 7 and 8 are details of auxiliary valves.

In the clutch shown in Fig. 1 the cylinders a^1, a^2, a^3 and a^4 are formed in one mem-

ber adapted to be rotatably connected to the power member k which may be the fly-wheel clutch member of an engine or other motive power generator. The ends of these cylinders are closed by caps d^1 , d^2 , d^3 and d^4 . The pistons b^1 , b^2 , b^3 and b^4 are provided with suitable fluid tight piston rings or cup leathers m secured by bolts m^1 . The oppositely disposed pistons are connected together by means of a yoke or frame f adapted to slide with their outer sides against the guiding members g^1 secured to the casing g . Motion from the said frame f to the cranks or eccentrics c^1 or c^2 of the driven shaft c is transmitted by means of bearing pieces h^1 and h^2 curved on their inner sides to fit the said cranks or eccentrics and adapted on their outer sides to bear against and reciprocate on the inner faces f^1 , f^2 of the frame f . The closed passage connecting the inlets to the cylinders a^1 and a^2 is shown at n^1 , a similar passage n^2 being arranged between the cylinders a^3 and a^4 . These passages are adapted to be controlled by hydrostatically balanced valves j^1 and j^2 provided with spindles j^3 extending through fluid tight stuffing boxes g^2 to a yoke j^4 connected to a boss j^5 slidably mounted on the shaft c along which it is adapted to be moved by hand-operated mechanism connected to the non-rotary members j^6 .

It will be understood that by moving the valves j^1 and j^2 by means of the hand operated mechanism j^6 to a position where the valves will close the passages n^1 and n^2 no fluid will be allowed to pass from the cylinder a^1 to the cylinder a^2 or from the cylinder a^3 to the cylinder a^4 and the clutch will be locked in such a manner that the driven element will rotate at the same speed as the driving element, and it will also be evident that by partly closing the said valves a corresponding reduction in speed will take place according to the speed at which the fluid passes along the closed passages from one cylinder to the other.

In the construction shown in Fig. 6 the controlling valves as well as being mechanically operable by means of the yoke ring j^4 which in this construction is mounted upon and supported by the valve rods j^3 and may be moved, together with said valve rods axially of the bearing p^1 by any desired mechanism, can be operated hydraulically by means of fluid from a source of fluid under pressure under the control of a hand operated valve. Said yoke ring is attached to the stems of the said valves as shown and is within easy reach and hence can be operated by hand in order to actuate said valves. The said fluid under pressure is admitted to the clutch through the opening p in the fluid tight bearing p^1 which communicates by means of a running joint with the fluid passages p^3 leading to the end of the cylinder

controlling valves j^{13} and j^{14} . These valves are returned to their normal position by means of springs j^{15} when the supply of fluid under pressure is cut off. The said running joint is also used to admit fluid by means of the passages p^4 Fig. 4, to the closed fluid passages n^3 and n^4 of the radial cylinders. The passages p^4 are provided with spring-controlled non-return valves e^1 . These valves may be provided with means for neutralizing the action thereon of centrifugal force, in a manner similar to that hereinafter described with reference to the valves e^1 and e^2 .

Each valve j^{13} , j^{14} is adapted to control two ports (not shown), each of which leads to one of a pair of communicating cylinders. Hence said valves are hydraulically balanced as the hydraulic pressure is always between the two bearing ends of the valves.

In the construction shown in Figs. 4 and 5, two sets of four radial cylinders arranged with their axes 90° apart are shown. Each set of four cylinders are arranged in one plant, the oppositely disposed pistons being connected by yokes f^2 and f^3 in a similar manner to the construction described with reference to Fig. 2. In order to allow of the yokes of the two pairs of diametrically arranged pistons working freely at right angles to each other, the yoke of one pair of pistons has a frame consisting of two pieces f^{11} and f^{12} arranged on each side of the frame f^3 of the other pair of diametrically arranged pistons. The yoke frames f^{11} and f^{12} are secured to the pistons b^5 and b^6 , while the yoke frame f^3 is secured to the other pair of pistons arranged at right angles to the first pair. In order to allow of freedom of motion of the pistons b^5 and b^6 with respect to the yoke frame f^3 of the other pair of pistons at right angles to them, they are grooved as shown at f^4 and f^5 between the portion of the pistons secured to the yoke frames f^{11} and f^{12} , and in order to allow of the corresponding motion of the other pair of pistons arranged at right angles to this pair, they are cut away at each side of the portion secured to the yoke frame f^3 as shown at f^6 and f^7 on the second set of four pistons.

The driven element or shaft of the clutch is mounted in suitable bearings in the main casing of the clutch, which may be plain bushed bearings as shown at c^3 and c^4 Fig. 1, or a combination of plain and roller bearings as shown at c^5 and c^6 Fig. 4.

The said closed fluid passages leading to the cylinders are provided with a safety valve e^1 and a non-return fluid replenishing valve e^2 preferably arranged in the cylinder caps as shown at d Fig. 2. In order to neutralize the action of centrifugal force on these valves, each of them is arranged in contact with one end of a lever having a balance weight at the other end and pivoted

so as to freely oscillate in a plane wherein both ends of the lever will be subjected to the action of centrifugal force.

Any suitable means may be employed for supplying fluid to the closed fluid circuit.

While I have herein shown and described a preferred form of my invention, I would have it understood that changes may be made in the form, proportions and construction of the several parts, within the scope of the appended claims.

What I claim and desire to secure by Letters Patent is:—

1. A hydraulic power transmitting shaft 15 clutch comprising in combination a driving member, a driven member, a plurality of cylinders rigidly carried by one of said members radially disposed with respect to the axis of rotation thereof, pistons reciprocable within said cylinders, means provided on the other of said members for reciprocating said pistons within said cylinders upon relative rotation of said clutch members, a passage parallel to the axis of rotation of the clutch members and connecting one of said cylinders with another of said cylinders in a different plane perpendicular to the axis of rotation of the said clutch members, and a hydraulically balanced valve adapted to be reciprocated longitudinally within said passage for controlling the flow of liquid in said passage.

2. A hydraulic power transmitting shaft clutch comprising in combination a driving member, a driven member, a plurality of cylinders rigidly carried by one of said members radially disposed with respect to the axis of rotation thereof, pistons reciprocable within said cylinders, means provided on the other of said members for reciprocating said pistons within said cylinders upon relative rotation of said clutch members, a passage parallel to the axis of rotation of the clutch member and connecting one of said cylinders with another of said cylinders in a different plane perpendicular to the axis of rotation of the said clutch members, and means including a valve adapted to be reciprocated longitudinally within said passage for controlling the flow of liquid in said passage and fluid passages adapted to afford communication by means of a fluid tight running joint between said valve and a non-rotary member communicating with a source of fluid under pressure whereby said valve can be operated hydraulically.

3. A hydraulic power transmitting shaft clutch comprising in combination a driving member, a driven member, a plurality of cylinders rigidly carried by one of said members radially disposed with respect to the axis of rotation thereof, pistons reciprocable within said cylinders, means provided on the other of said members for recip-

rocating said pistons within said cylinders upon relative rotation of said clutch members, a passage parallel to the axis of rotation of the clutch members and connecting one of said cylinders with another of said cylinders in a different plane perpendicular to the axis of rotation of the said clutch members, a safety valve provided in connection with the enclosed space formed by the said two cylinders and closed passage, 75 a lever and balance weight, said lever contacting with said safety valve whereby the same is rendered unaffected by the action of centrifugal force and a hydraulically balanced valve adapted to be reciprocated 80 longitudinally within said passage for controlling the flow of liquid in said passage.

4. A hydraulic power transmitting shaft clutch comprising in combination a driving member, a driven member, a plurality of cylinders rigidly carried by one of said members radially disposed with respect to the axis of rotation thereof, pistons reciprocable within said cylinders, means provided on the other of said members for reciprocating said pistons within said cylinders upon relative rotation of said clutch members, a passage parallel to the axis of rotation of the clutch members and connecting one of said cylinders with another of said cylinders in a different plane perpendicular to the axis of rotation of the said clutch members, and means including a non-return valve for maintaining said two cylinders and said closed fluid passage full under all working conditions, a loaded rocking lever contacting with said non-return valve whereby the same is rendered unaffected by the action of centrifugal force and a valve adapted to be reciprocated longitudinally within 105 said passage for controlling the flow of liquid in said passage.

5. A hydraulic power transmitting shaft clutch comprising in combination a driving member, a driven member, a plurality of cylinders rigidly carried by one of said members and radially disposed with respect to the axis of rotation thereof, pistons reciprocable within said cylinders, means provided on the other of said members for reciprocating said pistons within said cylinders upon rotation of the clutch members relative to one another, a closed fluid passage parallel to the axis of rotation of the clutch members and connecting one of said cylinders with another of said cylinders, the two last mentioned cylinders being parallel to one another and both disposed on the same side of the said axis of rotation, means including a non-return valve 110 for maintaining the enclosed space formed by said two cylinders and said closed fluid passage full, a safety valve provided in connection with the said enclosed space, both said non-return valve and said safety valve 115 120 125 130

being provided with a loaded rocking lever whereby they are rendered unaffected by the action of centrifugal force, a valve adapted to be moved longitudinally within said passage for variably obstructing said fluid passage and fluid passages adapted to afford communication by means of a running fluid

tight joint between said valve and a non-rotary member communicating with a source of fluid under pressure whereby said valve 10 can be operated hydraulically.

In witness whereof I affix my signature.

HENRY SELBY HELE-SHAW.
